UNITED STATES PATENT OFFICE.

GUSTAV BOESCH, OF DANBURY, CONNECTICUT.

PLUCKING MACHINE.

Application filed July 14, 1920. Serial No. 396,269.

To all whom it may concern:

Be it known that I, GUSTAV BOESCH, a citizen of the United States, and a resident of Danbury, county of Fairfield, and State of Connecticut, have invented an Improvement 5 in Plucking Machines, of which the following is a specification.

This invention relates to the art of fur preparation, and with regard to its more 10 specific features to apparatus for plucking the projecting hair from fur pelts or skins. One of the objects of the invention is to provide a fur plucking machine which shall be simple and durable in construction, and 15 reliable in action.

Another object is to provide a machine of the above type which shall speedily and effectively pluck the hair projecting from the surface of the fur proper, without danger of 20 damaging the fur.

Other objects will be in part obvious and in part pointed out hereinafter.

The invention accordingly consists in the features of construction, combination of elements and arrangement of parts which will be exemplified in the construction herein-after set forth, and the scope of the application of which will be indicated in the following claims.

30 In the accompanying drawings wherein is shown one of various possible embodiments of the several features of this invention,

Fig. 1 is a top view of my machine,

35 Fig. 2 is a transverse section taken along the line 2—2 of Fig. 1,

Fig. 3 is a fragmentary sectional view taken along the line 3—3 of Fig. 2, and

40 Fig. 4 is a sectional view taken along the line 4—4 of Fig. 2; Fig. 5 shows the operating members in front view.

Fig. 6 is a detailed view showing the adjusting and locking means for my skin holding frame; and

45 Fig. 7 is a detailed view of certain of the clamping and locking members thereof.

Similar reference characters refer to similar parts throughout the different views of the drawings.

50 Referring now to the drawings and more particularly to Figs. 1 and 2, I have shown a base 1 for my machine, preferably resting

on standards 2. Rigidly connected to the top of the base, are supports 3, 4 and 5, which are aligned to carry the power shaft 6, preferably extending beyond support 5 and having mounted upon said extension a pulley 7 through which driving power may be applied.

The shaft is preferably lodged in ball 60 bearings 8' (see Fig. 4) within supports 4 and 5.

Rigidly mounted on shaft 6 and extending into close proximity of the adjacent sides of supports 3 and 4, is an operating member 8. This operating member (see Figs. 3 and 5) preferably comprises a hub 9 and a plurality of outwardly extending blades 10, having blunt edges 11. The edges 11 of the blades are preferably helical in form, as shown at 12, and also intersect the hub 9 in a helical line 13. Each blade is curved along any section taken transversely thereof, as shown in Fig. 3, the concavity of said curvature preferably extending in one direction 65 as shown in Fig. 3. The pitch of each blade is preferably such that a plane through the axis of the operating member and an end of any blade will intersect an adjoining blade. 70

The purpose of this construction will appear more fully in the description of the 75 operation below.

Integral with support 4 and extending upwardly along one side thereof is a post 14 (see Fig. 4). A cover member 15, formed of 80 a suitable single sheet or plate metal, extends along the other side of the support 4 and is suitably secured to the support 4 by means of screws 18. The cover member 15 is bent 85 so as to form a transversely extending element 17 extending across the top of the post 14, thus forming a rectangular compartment 19 between the said members. A journal box 20 having a ball bearing 21 therein for supporting the shaft 22 parallel to the shaft 6, is housed within the compartment 19.

The shaft 22 carries a roller 23, of any suitable resilient material, adapted to contact with the blades 12 of the operating member 8.

The above description with regard to the support 4 and its detailed construction is applicable in substantially every detail to support 3, it being understood that the shaft

22 is supported within ball bearings 21 in turn supported in the journal box 20 housed within each support.

I preferably interconnect the journal boxes 20, for adjustably securing the roller 23 with respect to the operating member 8, and employ means which prevent displacing shaft 22 out of parallelism with shaft 6. For this purpose, I prefer to employ the following specific construction.

Secured to the top of each supporting member 3 and 4, and extending between them, I provide a stationary bridging member 24, (see Figs. 2 and 4) having legs 25, 15 one resting on each of supports 3 and 4, each leg being provided with a lug 26 for securing the bridging member to the top of the support by screws 28. The screws 28 extend through cover 17 into extension 14 and thus serve also to retain in position the housing or casing 15.

The legs 25 are provided with longitudinally extending openings 30 each adapted to receive a rod 32, which may take the form of a screw if desired, threaded into the journal box 20 for governing the position in the vertical plane of the shaft 22 with respect to the shaft 6. A spring 59 surrounds the journal box controlling rod 32 30 and abuts against the head 32' thereof and the cover member 17, thus tending to urge the controlling rod 32 with its attached journal box 20 in an upward direction.

I provide a secondary bridging member 33 35 (see Figs. 1 and 2) superimposed upon the bridging member 24 and provided with downwardly extending rods 31 suitably secured thereto and adapted to enter the opening 30 (see Fig. 4) in the upright members or legs 40 25 and to contact with the upper ends of the controlling rods 32. A screw 34 provided with a winged head 36 extends through a centrally located opening in the secondary bridging or adjusting member 33 and is 45 threaded into the central portion of the bridging member 24, the latter being provided with a boss 35 for increasing the extent of the engaging threaded portions of the screw 34 and the bridging member 24.

50 Manual operation of the screw 34 by means of the winged head 36 carries the adjusting bridge 33 with its associated rods 31 downwardly, the latter in contacting with the controlling rods 32 causing a like movement of the bearings 21 and the shaft 22 with its 55 associated roller member 23. Thus the degree and intensity of contact of the roller 23 with the blades 12 of the operating member 8 may be manually adjusted and predetermined. It will thus be seen that the bearings 21 housed in the journal boxes 20 are reliably and dependably controlled by the adjustable bridging member 33 and that the mechanical connection between the journal boxes 20 and 60 the adjustable bridging member 33 is not

only such that the positive adjustment of the journal boxes 20 and hence of the roller 23 with respect to the operating member 8 may be made to take place, but also is such that accessibility to the several parts for repair or replacement is materially enhanced. In this connection it may be noted that the adjustable bridging member 33 may be readily removed simply by removing the adjusting screw 34 from the stationary bridging member 24, whereupon the chambers or openings 30 are at once made accessible to permit ready access to the controlling rods 32 and associated parts.

Substantially enclosing the operating member 8 and roller 23, I preferably provide a hair box 37 (see Fig. 3) which comprises frame members 38 having an exhaust passage 39 and a hood 40 hingedly supported as at 41, to extend over roller 23. This hair box 45 also includes a shield 42 secured as by a slotted extension 42' thereon to an upstanding lug 44 (see Fig. 2) on base 1 by means of the bolt 43. The shield 42 is thus adjustable in a vertical direction and is adjustable also about the axis of the bolt 43, such adjustment permitting the upper edge 45 to be brought into the proper proximity to the edges 11 of the blades of the operating member 8. Any suitable means may be used to prevent air from entering between the rotating member 8 and the member 38 but preferably the hair box 37 is further provided with a member 90 bolted to the extension 94 of one of the sides 38 of the box 37 by means of the bolt 91 passing through the elongated slot 93 of the member 90. This member 90 functions to further enclose the member 8 and to prevent excess air from entering between the lower blades of the member 8 and the lower side of the hair box 37.

To place the skin to be treated in proper relation to the operating elements, and to hold it there for treatment, I provide a work carriage to be now described:

Two parallel rods 46 and 47 (see Figs. 1 and 2) are provided, extending transversely of base 1, one near each end of said base. Rod 46 passes through a corresponding opening in support 5, and rod 47 extends through a sleeve-like lug 77 cast upon base 1.

The base 1, is preferably provided with integral rearwardly directed extensions, near the ends of which are provided integral upstanding lugs 78' and 79', through suitable openings of which the rear ends of rods 46 and 47 respectively, extend. Each rod thus passes through two aligned openings of substantially the same size as the rod, and the rods are thus kept in proper parallel alignment.

Secured to the forward end of each rod, I provide a fixture generally indicated in Fig. 6 at 46', only one of which need be described, as the two are identical. This

fixture 46', is formed at its lower end to provide a sleeve member 47' at the bottom, fitting over the end of the rod and affixed thereto by set screw 48'. Extending upwardly from the forward end of sleeve 47', the fixture is formed with an upwardly directed extension 48 perpendicular to the rod and from the rear of the extension 48, there extends transversely of the rods 46 and 47, 10 a second sleeve 49' (see Fig. 1). Through the sleeves 49' of the two fixtures 46', there extends a transverse rod 50, more clearly shown in Fig. 1 secured at each end to one of said sleeves by a set screw 51' (see Fig. 6), the rod 50 being thus rigidly bridged across the forward ends of the two main supporting and parallel rods 46 and 47.

Secured to rod 50, I provide a transverse 20 attaching or supporting member 70', (see Figs. 1 and 7) for the skin support, this member extending longitudinally of the rod 50 and having integral sleeves 54 and 55, one preferably at each end, through which 25 the rod 50 passes. Opposite the sleeves 54 and 55 integral therewith and at right angles thereto there are provided socket members 54' and 55' respectively, within which extend the ends of the skin supporting member 52. This member is preferably formed of an integral strong steel rod, bent to have its two ends 52' and 52'' parallel to each other, and to provide a skin supporting section 52 parallel to shaft 6. The 30 parallel ends 52' and 52'' respectively, fit within sockets 55' and 54' and are secured therein by set screws 80'.

The elevation of the skin supporting rod 52 may be adjusted by rotation of the rod 52 with its auxiliary supporting member 70' about rod 50.

To lock the skin supporting member with 35 the pelt supporting rod 52 at any desired elevation, I preferably provide the following means, referring particularly to Figs. 6 and 7:

Centrally mounted upon rod 50, is a clamping fixture 64 more clearly shown however in Fig. 1. This fixture is preferably sleeved upon rod 50 as at 64' and is 40 secured thereto by set screws 65. Integrally with said sleeved portion and at right angles thereto, there is a downwardly extending clamping plate 66, through which passes clamping screw 67, having an operating 45 handle 68. Cooperating with the clamping plate 66, I preferably provide an extension 69 integral with and central of supporting member 70', and extending downwardly therefrom in parallelism with clamping 50 plate 66 rigidly fixed to rod 50 as above described. I provide the extension 69 with an arcuate slot 71, through which the clamping screw 67 passes. It will thus be seen 55 that the elevation of the skin-supporting member 52 may be readily adjusted by ro-

tating the composite rod 52 with the auxiliary supporting member 70' about the transverse rod 50, and in Fig. 7 of the drawings these associated parts are shown in dotted line position to indicate more clearly the 70 manner in which the adjustment may be brought about.

To arrange for moving the pelt toward or from the cutting element, I preferably attach a push strap construction 74 to the 75 upwardly directed extensions 48 of fixtures 46', by means of bolts 73.

The push strap consists preferably of a transverse sheet metal member 74, having integral end extensions 75, and 76, inclined 80 toward each other (see Fig. 1), a leather or cloth band 72 being attached to these extensions. For durability of construction each end of the cloth or leather member 72 is preferably overlapped as at 79, and a re-enforcing plate 80 is provided on the exterior thereof for clamping the member to the extensions, as by screws 78. The extreme ends of the member 74 are preferably curved 85 inwardly as at 81, to avoid presenting any 90 cutting edges to contact with the strap member 72. The flat upwardly directed extensions 48 to which the push strap construction is attached, are preferably provided with a series of aligned bolt openings 82 95 (see Fig. 6) to make possible the securing of this push strap construction to any pair of such openings in order to adjust the belt for convenient operation to persons of different height.

To compel return of the pelt holding construction to its original position, I preferably encircle rods 46 and 47 with coil springs 83 and 84 (see Fig. 1) respectively, the rear ends of said coil springs contacting with lugs 78' and 79', respectively, and the forward ends contacting collars 85 and 86 respectively, secured to the rods by set screws as shown at 87. The operator as is apparent may thus push the work carriage against 100 the opposition of springs 83 and 84 through a distance depending on the length of the fur on the skin, the spring when compressed limiting the approach of the skin holding member toward the stationary knife or the operator may control the inward movement of the work carriage with the pelt or skin supported thereon at will, as will be readily apparent. Thus, in Fig. 1 the parts thus moved inwardly toward the operative mechanisms are shown in dotted line position.

It will be noted also that collars 85 and 86 limit the return movement of the carriage to the inoperative position, by contact one with support 5 and the other with sleeve-like lug 77.

The operation of my machine is substantially as follows:

The operator having adjusted the position of push strap 72, to suit his height, by se- 130

curing bolts 73 in the proper openings 82, he adjusts the skin supporting rod 52 to the proper height by loosening the single clamping screw 67, rotating the skin supporting member 52 with supporting members 70', (which rotation, it will be understood, swings about the rod also the downwardly extending plate 66 with respect to the relatively fixed extension 69) about rod 50 until the proper height is reached and then tightening clamping plate 66 to extension 69, of the member 70', by controlling the clamping screw 66 by means of handle 68. No care need be taken in this adjustment to maintain the pelt supporting rod 52 in parallelism with the stationary knife, as this is inherently insured by the manner of mounting.

The operator, having placed the pelt to be treated upon the pelt supporting rod 52, with the fur extending toward the operating members 8 and 23, then presses with his body against push strap 72 until the skin comes into proper proximity to the operating members as shown in Fig. 3. He then draws the pelt back and forth across rod 52.

The shaft 6 being set into rotation at a high rate of speed in the counter clockwise direction shown in Fig. 3, a substantially enclosed chamber will be formed as shown in Fig. 3, between the hood member 40, roller member 23, upstanding blade 10, the hub member 9, horizontal blade 10 extending to the right, and shield member 42, and the pelt itself. As the operating member is rapidly rotated, it creates a suction, drawing the projecting hair of the fur inwardly between the blades and the roller member. The blade causes the contacting surface of roller 23 to rotate therewith. As the hair is firmly gripped between the dull edge of the blade and the resilient roller member, the hair will be pulled upon sufficiently before the blade comes out of contact with the roller, to pluck out the hair which has been gripped.

Since the pitch of the blades is such that before any blade has cleared the roller 23, the subsequent blade comes into contact with said roller, it is seen that the plucking action is continuous and that the roller is set into continuous rotation by said operating member 8 at substantially the same rate as said operating member, but in the opposite direction of rotation.

In some of the claims I use the term "locus of operation of a blade." By this term I designate the surface of revolution generated by the operation of the blade.

As any blade clears the roller member 23, the centrifugal force exerted upon the adjoining air by the high rate of rotation of the operating member, brings about automatic removal of any hair clinging to the blades.

When the blades or the roller, or both, have become worn to such an extent as to cease to exercise sufficient gripping action upon the hair to be plucked, it is merely necessary to tighten screw 34 (see Fig. 2). 70 This tightening action will move bridging member 33 downwardly, and with it rods 32 and their attached journal boxes 20, whereupon the proper pressure between the members will be restored. If it is desired to gain access to roller 23, hinged hood 40 need merely to be turned back.

It will thus be seen that there is herein described apparatus in which the several features of this invention are embodied, 80 which apparatus in its action attains the various objects of the invention and is well suited to meet the requirements of practical use.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

I claim as my invention:

1. In apparatus of the character described, in combination, a resilient rotatable member, a second cooperating rotatable member, means for positively driving one of said members, and means associated with said second member adapted and formed to effect substantially uninterrupted gripping and plucking of hair by cooperation with said first member, said latter means operating to transmit a continuous driving force from said positively driven member to said other member. 95

2. In apparatus of the character described, in combination, a roller member, a cooperating rotatable member, means for positively driving said latter member, and means on said latter member for transmitting a continuous driving force to said roller member, said means in cooperation with said roller, operating to pluck hair. 110

3. In apparatus of the character described, in combination, a cylindrical roller member having a yielding surface, a cooperating rotatable member having an axis parallel to that of said roller member and carrying operative members spaced angularly from one another in any plane taken transversely to the axis of said rotatable member, said operative members having edges adapted upon rotation of said rotatable member to generate a cylinder continuously tangential to said roller member, thereby to permit one of said rotatable members to be continuously driven from the other, and means for driving one of said rotatable members, said operative members co- 120 125 130

acting with said roller member to grip and pluck hair presented therebetween.

4. In apparatus of the character described, in combination, a rotary operating member having a plurality of blunt blades, and a roller tangential to the locus of said blades, and rotatable with each blade as said blade contacts therewith, the subsequent blade contacting said roller prior to clearance thereof by the preceding blade.

5. In apparatus of the character described, in combination, a rotary operating member having a plurality of blunt helical blades, and a roller tangential to the locus of said blades, means for driving said rotary operating member, whereby said roller is driven by contact with said blades, the blades having a pitch, to cause any blade to contact said roller prior to clearance thereof by the previous blade.

6. In apparatus of the character described, in combination, two rotatable members, means for positively rotating one of said members, and means associated with one of said members adapted to make continuous contact with and thereby to rotate the other of said members and acting to bring about a draft to draw hair between said members to permit plucking thereof.

7. In apparatus of the character described, in combination, a rotary operating member, a roller, a hair box having an inner surface in close proximity to the path of said rotary member, means for positively driving said operating member, said operating member having means continuously touching said roller to grip hair at said touching points.

8. In apparatus of the character described, in combination, a rotary operating member having a plurality of blunt helical blades, and a roller tangential to the locus of said blades, means for driving said rotary operating member, whereby said roller is driven by contact with said blades, the blades having a pitch, to cause any blade to contact said roller prior to clearance thereof by the previous blade and a hair box having an inner surface in close proximity to the path of said blades.

9. In apparatus of the character described, in combination, a frame member having two oppositely disposed supports each provided with a guideway, a rotary operating member rotatably supported by said frame, a journal box slidably mounted in each of said guideways, a second rotary member supported in said journal boxes and adapted to coact with said first-mentioned rotary member, a housing associated with each of said supports and extending in substantial alignment with said guideway, a controlling member slidably mounted in each of said housings and engaging at its lower end one of said journal boxes, each of

said controlling members being of less longitudinal extent than its associated housing, a bridging member extending across said two supports and having at its respective ends a projection extending slidably into one of said housings and engaging the controlling member therein, and means detachably mounting said bridging member with respect to said supports to permit removal thereof and adapted also to permit said bridging member to be adjusted toward or away from said housings.

10. In apparatus of the character described, in combination, a frame member having two oppositely disposed supports each provided with a guideway, a rotary operating member rotatably supported by said frame, a journal box slidably mounted in each of said guideways, a second rotary member supported in said journal boxes and adapted to coact with said first-mentioned rotary member, a housing associated with each of said supports and extending in substantial alignment with said guideway, a controlling member slidably mounted within each housing and rigidly connected at its lower end to one of said journal boxes, said controlling member being of less longitudinal extent than said housing, spring means mounted within said housing and acting upon said controlling member to move said member with its associated journal box outwardly toward the open end of said housing, a bridging member extending across said supports and having at its respective ends a projecting member adapted to extend inwardly into one of said housings to engage the upper end of said controlling member, and means for adjusting said bridging member toward or away from said housing to oppose the action of said spring means or to permit said spring means to move said controlling members toward the open ends of said housings.

11. In apparatus of the character described, in combination, a rotary operating member, a roller cooperating therewith, journal boxes for said roller, a bridging member carrying said journal boxes, a fixed member, a single member for adjustably securing said bridging to said fixed member, and means to insure adjusting movement of said roller parallel to itself.

12. In apparatus of the character described, in combination, a rotary operating member, a roller cooperating therewith, journal boxes for said roller, a bridging member carrying said journal boxes, a fixed member, and a single screw member for adjustably securing said bridging to said fixed member.

13. In apparatus of the character desired, in combination, a rotary operating member, a roller cooperating therewith, journal boxes for said roller, a fixed bridg-

- ing member, a second bridging member carrying said journal boxes, and a single means for adjustably securing said second to said fixed bridging member. 65
- 5 14. In apparatus of the character described, in combination, a rotary operating member, a roller cooperating therewith, journal boxes for said roller, a fixed bridging member, a second bridging member carrying said journal boxes in the guideways provided therefor, and a single means for adjustably securing said second to said fixed bridging member said bridging members having cooperating means to guide 10 movement of said roller parallel to itself. 70
- 10 15. In apparatus of the character described, in combination, a rotary operating member, a roller cooperating therewith, journal boxes for said roller, a bridging member comprising two parallel rods perpendicular to said roller, one connected to each said journal box, and a cross member connecting said rods, a fixed bridging member having paths for said rods, and a single 15 means for adjustably securing said first to 75 said fixed bridging member. 80
- 20 16. In apparatus of the character described, in combination, a rotary operating member, a roller cooperating therewith, journal boxes for said roller, tracks for permitting adjustment of the elevation of said journal boxes, upwardly extending vertical rods, one secured to each journal box, a fixed bridging member, having two tubular openings, one for each said rod, a cross member connecting said rods, and a single screw 25 means for adjustably securing said cross member to said fixed bridging member. 85
- 30 17. In apparatus of the character described, in combination, a rotary operating member, a roller cooperating therewith, journal boxes for said roller, means cooperating with a pair of bridge members for adjusting the pressure of said roller against 35 said operating member, and spring means for relieving said pressure. 90
- 35 18. In apparatus of the character described, in combination, a rotary operating member, a roller cooperating therewith, journal boxes for said roller, a single means 40 cooperating with a pair of bridge members for adjusting the elevation of said roller in one direction, and spring means opposing said last means. 95
- 45 19. In apparatus of the character described, in combination, a plurality of supports, a rotary operating member journalled in said supports a roller cooperating therewith, journal boxes for said roller, tracks 50 in said supports to permit adjustment of said journal boxes, a member bridging and secured to said journal boxes, spring means pressing against said supports and said bridging member to urge said roller up- 55
- ward, and a single means for adjustably securing said bridging member relative to said supports. 60
20. In apparatus of the character described, in combination, a plurality of supports, a rotary operating member journalled in said supports, a roller cooperating therewith, journal boxes for said roller, tracks for permitting adjustment of the elevation of said journal boxes, upwardly extending vertical rods, one secured to each journal box, a fixed bridging member, having two tubular openings one for each said rod, a projection on each rod, a spring extending within said tubular openings and between a support and a projection, a cross member connecting said rods and a single screw means for adjustably securing said cross member to said bridging member. 70
- 70 21. In a machine of the class described, in combination a frame, having a pelt holding element, and a single means for adjusting the height of said element, and securing it against displacement. 75
22. In a machine of the class described, in combination, a frame having a pelt holding element, a shaft about which said frame may be adjusted for fixing the height of said element, and a single means for locking said frame against displacement. 80
23. In apparatus of the character described, in combination, a hair-operating element, a pelt-holding member mounted to be parallel to the locus of operation of said element, means rigidly mounting said pelt-holding member in said parallel relation 90 with respect to the locus of operation of said element, and means for adjustably positioning and locking said mounting means to permit adjustment of the position of said pelt-holding member with respect to 95 the locus of operation of said element, thereby to maintain said parallel relation. 100
24. In a machine of the class described, in combination, a hair operating element, a pelt holding member parallel to the locus 110 of operation of said element, and means to permit adjustment of the position of said pelt holding member about an axis parallel to itself. 115
25. In apparatus of the character described, in combination, a hair-operating element, a pelt-holding member, a frame movable toward or away from the locus of operation of said element and along a pre-determined path, a shaft rigidly mounted 120 upon said movable frame and having its axis parallel to the locus of operation of said hair-operating element, and means pivotally mounted upon said shaft and adapted to be adjustably swung about the axis thereof for 125 supporting said pelt-holding element in parallelism with said shaft. 130
26. In apparatus of the character de-

- scribed, in combination, a hair-operating element, a pelt-holding rod, a frame movable toward or away from said hair-operating element and along a predetermined path and including a shaft rigidly supported by said movable frame, the axis of said shaft being parallel to the locus of operation of said element, an auxiliary frame member pivotally mounted upon said shaft and adapted to be angularly displaced about the axis of said shaft with respect to said movable frame, means for locking said two frames together, and means mounting said pelt-holding rod upon said auxiliary frame and in parallel relation with respect to the axis of said shaft. 65
27. In a machine of the class described, in combination, a hair operating element, a frame including a pelt holding rod, the latter being parallel to the locus of operation of said element, means to permit adjustment of said frame about an axis parallel to said rod, and a unitary clamp to lock said frame in its adjusted position. 70
28. In a machine of the class described, in combination, hair plucking means, including a rotary member having a plurality of blades, a frame including a pelt holding device, the latter parallel to the locus of said blades, a rod supporting said frame and about which said frame may be adjusted, a clamping plate apart from said frame, and a device for clamping an element of said frame to said clamping plate. 75
29. In a machine of the class described, in combination, hair removing means including a rotary member having a plurality of operating blades, a frame including a pelt holding device, the latter parallel to the locus of said blades, a rod supporting said frame and about which said frame may be adjusted, a clamping plate apart from said frame, an extension on said frame, a clamp passing transversely of said clamping plate and said extension, one of said latter elements having an arcuate path through which said clamp extends to permit adjustment. 80
30. In a machine of the class described, in combination, hair removing means, a work carriage including a rod, a pelt holding frame disposed about said rod for rotatable adjustment, a clamping plate rigid with said rod, and unitary means for clamping an element of said frame to said clamping plate. 85
31. In a machine of the class described, in combination, a pair of hair operating members, a work carriage including a rod, a frame disposed about said rod for rotatable adjustment, a clamping plate rigid with said rod, an extension on said frame, a clamping screw passing through said clamping plate and said extension, and an arcuate slot in said extension, through which said screw passes to permit adjustment. 90
32. In a pelt holding frame, a transverse attaching member having integral sleeve members at its ends, adapted to slip over a supporting rod, sockets transverse of said sleeves for securing the pelt holding element, and a transverse extension on said member adapted to permit adjustment of said pelt holding element with respect to said supporting rod, substantially midway between said sleeves. 95
33. In a machine of the class described, in combination, means for operating on the hair of a pelt, a frame having a pelt holding element, a shaft about which said frame may be adjusted for fixing the height of said element, a non-rotatable member, a single means for locking said frame against rotation to said member, and means for permitting sliding of all said members as a unit to place the pelt in proper proximity to said hair operating means. 100
34. In a machine of the class described, in combination, hair plucking means, a frame having a pelt supporting element, a lever for adjusting the height of said supporting element relative to said hair plucking means, means to change the distance between said hair plucking means and said supporting element, and means to prevent change in the direction of said supporting element. 105
35. In a machine of the class described, in combination, a rod, a frame mounted thereon for rotary adjustment about the axis of said rod, a pelt supporting element on said frame, and means for longitudinally moving said rod in a direction substantially perpendicular to its length. 110
36. In a machine of the class described, in combination, hair plucking means, a rod, a frame mounted thereon for rotary adjustment about the axis of said rod, means for securing said frame with respect to said rod in any position of rotary adjustment, means for longitudinally pushing said rod in a direction substantially perpendicular to its length to cause the pelt to approach said plucking means, and means to cause said rod to return when no longer pushed. 115
37. In a machine of the class described, in combination, hair plucking means, a pelt supporting frame, guide means to prevent any rotation of said frame about a vertical axis, a push strap for longitudinally moving said frame to bring the pelt in the path of said plucking means, and means to adjust said push strap for persons of different height. 120
38. In apparatus of the character described, in combination, a hair-operating element, a frame movable toward or away from the locus of operation of said hair-

operating means, a pelt-supporting member mounted upon said frame and movable therewith adapted to present said pelt to said hair-operating element, a transversely extending member associated with said frame adapted to be engaged by the body of the operator thereby to move said frame with said pelt-moving element toward or away from said hair-operating element, and

means for adjusting said transversely extending member with respect to said movable frame to adjust said member for persons of different height.

In testimony whereof, I have signed my name to this specification this first day of 15 July, 1920.

GUSTAV BOESCH.
